United States Patent Office

Des. 223,833
Patented June 13, 1972

223,833

VIDEOTELEPHONE TRANSCEIVER CONTROL UNIT

Henry Dreyfuss, South Pasadena, and Rembert Ryan Stokes, Middletown, Calif., assignors to Bell Telephone Laboratories, Incorporated, Murray Hill, N.J.

Continuation-in-part of design application Ser. No. 15,753, Feb. 12, 1969. This application Apr. 30, 1970, Ser. No. 22,733

Term of patent 14 years

Int. Cl. D14—03
U.S. Cl. D26—14

FIG. 3

FIG. 2

Des. 223,833

PAGE 5

FIG. 4

FIG. 6

FIG. 5

FIG. 7

FIG. 1 is a front perspective view of a videotelephone transceiver control unit showing my new design;

FIG. 2 is a front view of the control unit shown in FIG. 1;

FIG. 3 is a side view of the control unit shown in FIG. 1;

FIG. 4 is a front perspective view of a modified embodiment of the control unit illustrated in FIG. 1.

FIG. 5 is a front view of the control unit shown in FIG. 4;

FIG. 6 is a side view of the control unit shown in FIG. 4; and

FIG. 7 is a rear view of the control unit that is the same for both embodiments.

This is a continuation-in-part of design application Ser. No. D. 15,753 filed Feb. 12, 1969 and abandoned subsequent to the filing of this application.

We claim:

The ornamental design for a videotelephone transceiver control unit, substantially as shown and described.
